UNITED STATES PATENT OFFICE.

FREDERIC JOHN WHINCAP, OF STURGIS, MICHIGAN.

DESIGN FOR A CURTAIN ROD OR SIMILAR ARTICLE.

Application filed March 22, 1926. Serial No. 17,013. Term of patent 7 years.

To all whom it may concern:

Be it known that I, FREDERIC JOHN WHINCAP, a subject of the King of England, and a resident of Sturgis, in the county of St. Joseph, State of Michigan, have invented a new, original, and ornamental Design for a Curtain Rod or Similar Article, of which the following is a specification, reference being have to the accompanying drawing forming part thereof.

The drawing is a front perspective view of a curtain rod or similar article embodying the design of my invention.

I claim as my invention:—

The ornamental design for a curtain rod or similar article as shown.

FREDERIC JOHN WHINCAP.
